UNITED STATES PATENT OFFICE.

WILLIAM BLACKER, OF STALYBRIDGE, ENGLAND.

PUPPET-BLOCK, PUPPET, AND LIKE DEVICE USED IN CONNECTION WITH THE PRESSING, STAMPING, AND TREATMENT OF METALS.

1,323,001.

Specification of Letters Patent. Patented Nov. 25, 1919.

Application filed January 18, 1919. Serial No. 271,872.

To all whom it may concern:

Be it known that I, WILLIAM BLACKER, a subject of the King of Great Britain and Ireland, residing at 62 Stocks Lane, Stalybridge, in the county of Lancaster, England, engineer, have invented new and useful Improvements in Puppet-Blocks, Puppets, and like Devices Used in Connection with the Pressing, Stamping, and Treatment of Metals, of which the following is a specification.

This invention relates to puppet blocks, puppets, and like fittings, such as jingler blocks, which can be used with mechanical hammers or other stamping or pressing, 15 stripping, or like mechanism used in connection with the die stamping or pressing of metal, pressed die work, and such like.

It is known to use detachable puppets applied to a puppet block, the puppets having long shanks socketed in holes in the block each puppet being held by a cotter passed through a slot or opening in the puppet block and fitting a slot in the shank of the 25 puppet. Such detachable puppets are not only expensive to make as they require to be turned and fitted, but in some situations they are troublesome to apply and renew because of difficulty in getting at the cotters.

According to my invention, I fashion the puppet or other block, such as a jingler block, with a number of undercut grooves, or beveled edge channels or dove-tail guideways upon its upper face and radiating 35 from the center at which the dieblock or the like is applied. For example I may provide four undercut grooves, one at each corner of a square puppet block, although this may vary. Such undercut grooves are slightly 40 tapered, diminishing a little in width as the center of the puppet block is receded from.

I employ readily attachable and detachable puppet devices which are of metal and have their lower part or foot slightly tapered and also a little inclined whereby each 45 one can serve as a sliding block capable of engaging and locking with its particular undercut groove in the puppet block casting. In the case of four puppets to be fitted 50 they are separately applied by outward direction from the center of the puppet block by being knocked into position each to firmly engage its set of undercut grooves. Said undercut grooves firmly hold and support the puppets and yet allow of the ready

removal or renewal of a broken one; or if need be the use of puppets of different size or design.

I bore each puppet and tap the same for application of a screwed stud or spindle 60 which several screwed studs or spindles hold the die block as will be understood.

I also saw or cut each puppet longitudinally and down to the screw thread and apply transverse bolts with nuts or equivalent means, with the object of allowing me to clamp the adjustable holding screws for the die block or the like.

The invention is illustrated in the accompanying drawings in which:

Figure 1 is an elevation of a jingler block constructed in accordance with my invention, one of the puppets being removed, the view being an elevation of Fig. 2 looking in the direction of the arrow.

Fig. 2 is a plan view of Fig. 1.

The jingler block *a* is of ordinary or usual construction, such as is used with Oliver hammers.

Each corner of the block on its upper face 80 is cut at *b* to form a triangular gap and the upper surface of the block at these corners is formed with undercut or dove-tail grooves or ways *c* as clearly shown in both figures of the drawings where a puppet block 85 has been removed. The undercut grooves diminish in width outwardly, *i. e.* as they recede from the center of the block. Surrounding the die block *d* the surface of the block *a* is cut with an annular groove or gap 90 *f* down to or below the bottom level of the undercut grooves to facilitate the insertion of the puppet block and removal thereof.

The puppet devices *g* under my invention, which are readily attachable and detachable, are of metal and are formed with a foot *h* slightly tapered and inclined so as to engage with and lock in its particular undercut groove *c*. The four puppets shown are separately inserted in position from the 100 center and knocked or wedged into position each in its undercut groove, where they are firmly held and yet can be readily removed, in case it is necessary to renew a broken puppet or for using puppets of different size or design. Each puppet *g* is bored and tapped for a screwed stud *i* formed with square ends *j* to enable same to be rotated by a suitable key or other device, and with rounded heads *k* and these screwed studs 110

are adapted to hold the die block *d* as shown in the drawings. The puppets *g* are also cut longitudinally to form a slot *m* down to the screwed thread to enable the puppets 5 to be clamped firmly on the screwed studs *i* by means of transverse bolts *n*.

By my invention I can produce cheap and strong puppets and a puppet block capable of having my puppets readily applied there- 10 to, removed or renewed, the puppets serving to firmly support, bind and hold the adjusting screws which bear on and confine the die block or its like.

The bore and thread tapped in each pup- 15 pet may be at any desired angle and the actual design of the puppets may vary.

It might be possible in large sized pup- 20 pets to have projections from the puppet block engaging with an undercut recess in an applied puppet.

I declare that what I claim is:

1. In a device of the class described, the combination of a block, a die adapted to be seated thereon, a plurality of devices adapt- 25 ed to hold said die and comprising members slidably carried by said block and each having a threaded bore and a threaded stud rotatable in said bore and adapted to engage said die, and coöperating means carried by said block and said members for limiting the backward sliding of the mem- bers.

2. In a device of the class described, the combination of a block, a die adapted to be seated thereon, a plurality of devices adapt- 35 ed to hold said die and comprising members each having a threaded bore and a threaded stud rotatable in said bore and adapted to engage said die, said block and each of 40 said members having one a dove-tailed guide-way and the other a dove-tailed extension adapted to slide in said guide-way, said guide-ways and extensions being so formed as to limit the backward sliding of 45 said members.

3. In a device of the class described, the combination of a block, a die adapted to be

seated thereon, a plurality of devices adapt- 50 ed to hold said die and comprising members each having a threaded bore and a threaded stud rotatable in said bore and adapted to engage said die, the block having a dove- 55 tailed guide-way for each of said members and said members each having a dove-tailed extension adapted to slide in said guide- way.

4. In a device of the class described, the combination of a block, a die adapted to be seated thereon, a plurality of devices adapt- 60 ed to hold said die and comprising members each having a threaded bore and a threaded stud rotatable in said bore and adapted to engage said die, said block and each of said members having one a guide-way and the other an extension adapted to slide in said 65 guide-way, said guide-way and extension having their side walls converging from the center of said block thereby to limit the backward sliding of said members.

5. In a device of the class described, the combination of a block, a die adapted to be seated thereon, a plurality of devices adapt- 75 ed to hold said die and comprising members slidably carried by said block and each having a threaded bore and a threaded stud rotatable in said bore and adapted to engage said die, and means carried by said members for clamping said studs in the bores.

6. In a device of the class described, the combination of a block, a die adapted to be seated thereon, a plurality of devices adapt- 80 ed to hold said die and comprising members slidably carried by said block and each having a threaded bore and a threaded stud ro- 85 tatable in said bore and adapted to engage said die, said members each having a longitudinally extending slot communicating with said bore, and clamping bolts extending transversely of said slot thereby to clamp 90 said studs in the bores.

In testimony whereof I have signed my name to this specification.

WILLIAM BLACKER.
